KNITTED FABRIC AND METHOD OF
MAKING THE SAMEEugene St. Pierre, Pawtucket, R. I., assignor to
Hemphill Company, Central Falls, R. I., a cor-
poration of Massachusetts

Application August 15, 1938, Serial No. 224,873

8 Claims. (Cl. 66—172)

This invention relates to a knitted fabric and method of making the same and more particularly to knitted fabrics having an elastic thread or threads incorporated therewith in combination 5 with ornamental threads commonly known as wrap threads. While the wrap threads may be incorporated in a manner similar to that shown in Taubel Patent #1,619,788, March 1, 1927, they are herein shown as incorporated in a knitted fabric 10 in a manner similar to that shown in Lawson Patent #1,702,608, February 19, 1929.

In the drawings:

Fig. 1 is a view showing the outer face of the fabric and including a few wales and courses of 15 the fabric;

Fig. 2 is a view similar to Fig. 1 but showing the fabric distorted somewhat by reason of an elastic thread;

Fig. 3 is a view showing the movements of the 20 needles to engage the main thread, the elastic thread and one or more wrap threads;

Fig. 4 is a diagrammatic plan view supplementing Fig. 3;

Fig. 5 is a perspective view showing the position 25 the elastic thread takes with respect to the needles as the said needles pass the auxiliary feeding station; and

Fig. 6 is a conventional view of a stocking showing 30 a series of patterns similar to the one disclosed in Fig. 1.

Referring particularly to Fig. 1, courses 1 to 17 are shown, said courses including wales 18 to 30. The base fabric is knitted with one or more in- 35 elastic threads 31, fed through a guide 31', and which may hereinafter, for convenience, be referred to as being of cotton and an elastic thread 32 which may be of uncovered or covered rubber such as is commonly known as Lastex. In alternate wales 18, 20, 22, 24, 26, 28 and 30, etc., the 40 elastic thread 32 is shown as knitted by alternate needles 33 only. The cotton thread 31 is knitted by the said alternate needles 33 as well as the intermediate needles 34 which knit the intermediate wales 19, 21, 23, 25, 27, 29, etc.

45 By knitting the elastic thread 32 with the alternate needles 33, the intermediate wales 19, 21, etc., are forced to the outer face of the fabric, some of the said wales, as well as some of the alternate wales 18, 20, etc., being wrapped with 50 one or more wrap threads 35. The rib effect produced by the forcing of the intermediate wales to the outer face of the fabric, is due primarily to the elastic thread or strand 32 being between a loop of the cotton or other thread, e. g., the loop 36, Fig. 2, 55 and adjacent loops, e. g., 37 and 38, Fig. 2. In

other words, the rib effect is not due to the drawing together of the spaced intermediate wales by the elastic thread, the same being knitted under very light tension, that is, under what is commonly known as knitting tension similar to that disclosed 5 in the Sturgess British Patent #4418 of 1886.

The relatively inelastic, cotton thread 31 is knitted by all the needles at the main feeding station M while the elastic thread 32 is fed to and knitted by the alternate needles at the auxiliary 10 feeding station A. Knitting cams (not shown) act upon all of the needles in the usual or any desired manner at the main feeding station while alternate needles only are actuated by cams (not shown) at the auxiliary feeding station A, the 15 intermediate needles passing beneath the elastic thread 32 as indicated in Fig. 3. To select the needles preparatory to knitting at the auxiliary feeding station A, jacks may be provided which jacks are controlled to elevate needles that knit 20 alternate wales 18, 20, etc., only, just prior to the said needles reaching the cams at feeding station A. Other jacks which may include some of the mentioned jacks, act upon needles selectively to elevate them to a position to be wrapped by the 25 wrap thread, such as 35, which thread or threads is or are fed to the needles by means of the wrapping mechanism 39 which may be identical with or similar to the wrap mechanism illustrated in the Lawson Patent #1,702,608, February 19, 1929, 30 noting particularly the disc 117 and associated parts shown in the said patent. Between the auxiliary feeding station A and the wrap mechanism 39, a cam relowers the alternate needles that were elevated to knit the elastic thread 32, 35 such relowering being indicated by the inclined path 40 of the needles after they pass the guide 41 which feeds thread 32. The elastic thread is fed to the needles through a vertically disposed guide 41 which passes between the needles and the latch 40 ring (not shown). The guide 41 may be supported in any convenient manner and, preferably, on the latch ring.

It is desirable that the elastic thread 32 be fed 45 into the hooks of alternate needles with as little tension as possible consistent with the knitting of uniform fabric. The tension imposed upon the elastic is what may be termed, a light, knitting tension. The close feeding of the elastic thread 32 by the guide 41 making it unnecessary to impose any considerable tension upon the elastic thread 32 in order to cause the same to be fed into the hooks of alternate needles 33 and above the intermediate needles 34 so that upon elevation of the latter they shall pass forward of the elastic 50 55

thread. The lack of any substantial tension upon the elastic thread 32 causes the same to remain more or less in contact with the hooks of the needles which do not knit the said elastic thread, 5 as indicated in Fig. 5.

Fabric, as shown in the drawings and knitted as previously described, is essentially a two-feed fabric, alternate courses 1, 3, 5, 7, 9, etc., being knitted with the cotton or other relatively in- 10 elastic thread 31 with all the needles, while the intermediate courses 2, 4, 6, 8, 10, etc., are knitted by alternate needles only engaging and knitting the elastic thread 32 only.

The lack of substantial tension on the elastic 15 thread serves a useful purpose in that it permits the wrapping of consecutive needles of a group as distinguished from every other needle only which is necessary in order to obtain a satisfactory fabric when imposing substantial tension on an 20 elastic thread. However, any desired selection of needles may be utilized for wrap selection, in other words, any of the needles can be elevated to knit a wrap thread such as 35.

When knitting the base fabric only, i. e., without 25 wrap threads, the needles move along until elevated by the usual raise cam in advance of the guides, such as 31', the effect of the raise cam being indicated by that portion of the dot and dash line, Fig. 3, inclined upwardly and indicated 30 at 42. Subsequently to passing the guide 31', all of the needles move downwardly to the position 43 and knit the yarn 31; thereafter to the latch clearing position 44 then being moved down to move along the level 45, the cycle thereafter being repeated beginning with selection for the 35 elastic thread 32.

When knitting pattern fabric as by means of a wrap thread or threads 35, jacks (not shown) selectively elevate needles as indicated at 46, said 40 needles then moving along the horizontal path 47 where they receive a wrap thread or threads in their hooks, as indicated in Fig. 3. Thereafter the needles are depressed to join the non-wrap needles, the wrap needles then knitting the 45 cotton or other relatively inelastic thread 31' in the same manner as the non-wrap needles.

The wales 24, 26, etc. comprise loops of cotton or other relatively inelastic yarn 31 and elastic yarn 32, whereas the wales 25, 27, 29, etc., are 50 knitted of the cotton or other yarn 31 in every course, the elastic yarn 32 passing back of the said wales which constitute the face wales of the fabric. In the wrap areas, Fig. 1, wales, such as 20 and 22, are alternately knit with the elastic 55 yarn 32 and then with both the cotton or other yarn 31 and the wrap thread 35; in other words, the elastic thread in said wales 20 and 22, is drawn through two loops while the two loops of the yarn 31 and thread 35 are drawn through 60 single loops of the elastic thread 32.

When starting the knitting, a selvage may be 65 knitted by first causing the elastic thread to be fed to every other needle in the manner hereinbefore described for one or two courses, the cotton or other yarn then being fed to and knitted by all the needles in the usual manner. In knitting the 70 selvage as just described, the guide 31' is not moved to feeding position until all the alternate needles have engaged the yarn in their hooks or until said alternate needles have caught the yarn for two courses of knitting thus knitting the said elastic yarn during the second course.

The stocking 48 diagrammatically illustrated in Fig. 6, may include a rib top 49, the rib effect of 75 which is produced by knitting the base fabric in

the manner hereinbefore described. Within the base fabric, wrap or other design areas 50 may be incorporated, one form of such patterning being illustrated in Fig. 1. Subsequent to the knitting of the rib top 49, the remaining portion of the 5 stocking may be knitted in any desired manner. The rib stitches may extend into the leg, foot and other portions of the stocking, if desired.

The invention is preferably practiced upon a circular independent needle machine as illustrated in Figures 3 and 4. In operation, the circular knitting machine effects the knitting of what is commonly known as a seamless fabric, such as a stocking.

As hereinbefore described, the elastic thread 32 15 is, preferably, knitted by the alternate needles, but the elastic knitted thread may be fed to the alternate needles in such a manner as not to be knitted, one example of such feeding being disclosed in the Sturgess British Patent #4418 of 20 1886. Furthermore, regardless of whether the elastic thread is knitted or inlaid as disclosed in the Sturgess patent, a separate or relatively inelastic thread may be knitted by alternate or all of the needles at the auxiliary feeding station, in 25 addition to the inelastic thread 31 which is knitted by all the needles at the main feeding station.

The elastic thread 32 is knitted, as illustrated in Figures 1 and 6, in a sufficient number of 30 courses to give to the fabric the rib appearance normally resulting from the knitting of fabric upon two sets of opposed needles, notwithstanding the fact that the stocking is knitted plain, i. e., with one set of needles only. As specifically 35 herein disclosed, the elastic is knitted throughout the top 49 of the stocking as illustrated in Figure 6.

The terms employed in the foregoing description are used solely for the purpose of clearly 40 describing the knitted fabric and method of knitting, without the intention of limiting the invention to the precise methods of knitting and details of construction disclosed. As an example, "threads" and "yarns" are interchangeably used 45 to refer to 31, 32, or 35 without in any way calling for specific characteristics of the several threads or yarns other than that the thread or 50 yarn 32 must be relatively elastic.

In the foregoing description and in some of 50 the claims, reference has been made to "alternate" with respect to wales and courses; by "alternate" it is not intended to limit the invention to "every other" either as applied to wales or courses, as the elastic and inelastic courses may 55 alternate in other than in a one and one relation, e. g., one and two, two and one, and two and two.

As hereinbefore described, the elastic thread 32 is fed to the needles under a light tension, said 60 tension being sufficient to effect the proper placing of the said elastic thread with respect to the needles in the manner illustrated in Fig. 5. In other words, the amount of tension imposed upon the said elastic thread 32 is substantially the same as the amount of tension imposed upon the elastic 65 thread as disclosed in the Sturgess British Patent #4418 of 1886.

Although the description and some of the claims refer to the knitting of the thread 31 by "all" the needles, ornamental or other effects may be produced by occasionally omitting the knitting by 70 some of the needles.

I claim:

1. A plain knitted, seamless stocking fabric comprising wales and courses, a relatively in- 75

- elastic yarn alone knitted in alternate courses only and a relatively elastic yarn knitted in intermediate courses only, the relatively inelastic yarn being knitted at all of the wales in the said alternate courses and the said elastic yarn being knitted at alternate wales only in the said intermediate courses, the said elastic yarn being knitted under a light tension and in a sufficient number of courses to cause the intermediate wales to appear as rib wales on the outer face of the fabric.
2. A knitted fabric comprising wales and courses, a relatively inelastic yarn alone knitted in alternate courses only and a relatively elastic 15 yarn knitted in intermediate courses only, the relatively inelastic yarn being knitted at all of the wales in the said alternate courses and the said elastic yarn being knitted at alternate wales only in the said intermediate courses, and a wrap 20 thread knitted in some of the courses at some of the wales, the said elastic yarn causing the intermediate wales to appear as rib wales on the outer face of the fabric.
3. A method of knitting including feeding a 25 relatively inelastic yarn to all the needles at one feeding station, and feeding a relatively elastic thread to alternate needles only at a second feeding station, knitting the yarns separately at their respective feeding stations while imposing a light 30 knitting tension upon the elastic yarn, and wrapping some of the needles with an additional thread.
4. A method of knitting a stocking top on a circular knitting machine and including knitting 35 a relatively inelastic thread at one feeding station and knitting a relatively elastic thread at another feeding station and under a light tension only so that the elastic thread is engaged in the hooks of alternate needles and at the back of intermediate needles adjacent to the hooks 40 thereof.
5. A seamless plain knitted stocking top comprising, throughout the greater portion thereof, alternating courses of elastic and inelastic yarns, said inelastic yarn being knitted at every wale and said elastic yarn being knitted at alternate wales only and floated across intervening wales, said elastic yarn being knitted under light tension 5 and producing a rib effect.
6. A method of knitting a seamless stocking top with one set of independent needles, said method including feeding a relatively inelastic yarn to all the needles in alternate courses and 10 causing the said needles to knit the said yarn, and feeding an elastic yarn only to alternate needles, the said alternate needles knitting the said elastic yarn to constitute courses intervening between the first mentioned courses, and imposing 15 a light tension upon the elastic yarn, all for the purpose of causing alternate wales to appear as face wales in the knitted fabric.
7. A seamless plain knitted stocking top comprising, throughout the greater portion thereof, 20 alternating courses of elastic and inelastic yarns, said inelastic yarn being knitted at every wale and said elastic yarn being knitted at alternate wales only and floated across intervening wales, said elastic yarn being knitted under light tension 25 and producing a rib effect, one or more warp threads being knitted at some of the wales in some of the courses.
8. A method of knitting a seamless stocking top with one set of independent needles, said 30 method including feeding a relatively inelastic yarn to all the needles in alternate courses and causing the said needles to knit the said yarn, and feeding an elastic yarn only to alternate needles, the said alternate needles knitting the 35 said elastic yarn to constitute courses intervening between the first mentioned courses, imposing a light tension upon the elastic yarn, all for the purpose of causing alternate wales to appear as face wales in the knitted fabric, and wrapping 40 some of the needles during the knitting of some, at least, of the courses with one or more threads.

EUGENE ST. PIERRE.
